G. E. DAVIS.
AUTOMOBILE SIGNAL.
APPLICATION FILED APR. 6, 1920.

1,390,094.

Patented Sept. 6, 1921.

Inventor:
GEORGE E. DAVIS

BY *Victor J. Evans*
ATTORNEY

UNITED STATES PATENT OFFICE.

GEORGE E. DAVIS, OF HAMBURG, NEW YORK.

AUTOMOBILE-SIGNAL.

1,390,094.

Specification of Letters Patent. Patented Sept. 6, 1921.

Application filed April 6, 1920. Serial No. 371,633.

To all whom it may concern:

Be it known that I, GEORGE E. DAVIS, a citizen of the United States, residing at Hamburg, in the county of Erie and State 5 of New York, have invented new and useful Improvements in Automobile-Signals, of which the following is a specification.

This invention relates to a directional signal for automobiles and other vehicles the 10 principal object of the invention being to provide a device which will indicate when the vehicle is to change its course, the signal being so formed that it may be used as a parking lamp at night.

Another object of the invention is to provide a motor for moving the signal arm into and out of operative position and a switch located at a point adjacent the driver's seat for controlling the current to said motor.

This invention also consists in certain other features of construction and in the combination and arrangement of the several parts, to be hereinafter fully described, illustrated in the accompanying drawings and 25 specifically pointed out in the appended claim.

In describing my invention in detail, reference will be had to the accompanying drawings wherein like characters denote like 30 or corresponding parts throughout the several views, and in which:—

Figure 1 is a front view of the invention.

Fig. 2 is a longitudinal sectional view.

Fig. 3 is a sectional view showing the signal arm in operative position.

In these views 1 indicates a case which is connected to a bracket 2, said bracket being arranged to be clamped to the windshield frame of the automobile, though it 40 will be understood that the device may be secured to other parts of the vehicle. One side of the device is provided with a hinged door 3, the hinge 4 of which is connected with the lower end of the door. This door 45 is provided with a plate 5 which extends at right angles to the door and carries a signal lamp 6. The plate also carries a reflector 7 for the lamp and both the reflector and plate are provided with openings at the rear of 50 the lamp through which the rays of light therefrom may pass, the opening in the plate being covered by a transparent plate 8 which is preferably colored red. When the door is open it will be seen that a white light

will be projected forwardly while a red 55 light can be seen from the rear so that in this position of the door the device will act as a parking lamp, as well as a signal for indicating that the vehicle is to change its course of travel.

The means for opening and closing the door consists of a small electric motor 12 which is geared to a wheel 13 and this wheel is connected with the plate 5 by the link 14. This motor is controlled by the reversing 65 switch 15 which is located in convenient reach of the driver.

It will be understood that when the driver wishes to make a turn he operates the switch to cause the motor to turn in one direction 70 to open the door to display the signal. Wheel 13 will make a partial revolution and move link 14 to swing the door open. This link 14 striking the supporting frame of the motor will act as a stop to prevent further rotation of the wheel 13 and thus hold the door in open position. After he makes the turn the switch is turned in the other direction so as to reverse the motor to close the door. The switch is then turned to neutral 80 position.

I also provide an alarm 9 which is located in the motor circuit so that when the motor is moving the door to open position the alarm will be sounded.

I prefer to form an opening in the front of the case which will be in alinement with the lamp when the door is closed and to place a lens carrying member 16 in front of said opening and I may also place a mirror 90 17 on the rear said case thus the device can be used as a small head lamp and the mirror will give the driver a view of the road in his rear.

It is thought from the foregoing description that the advantages and novel features of my invention will be readily apparent.

I desire it to be understood that I may make changes in the construction and in the combination and arrangement of the several 100 parts, provided that such changes fall within the scope of the appended claim.

What I claim is:—

A signal of the class described comprising a casing having an opening in its front 105 face and a door opening in its outer edge, a lens covering the opening in the front face, a door for closing the door opening, said

door being hinged to the casing at its lower edge, a signal plate connected at one edge with the inner face of the door and extending at right angles to the door, a reflector carried by the plate, said plate and reflector having registering openings therein, an electric lamp supported by the reflector in aline-

ment with the openings, and means for opening and closing the door, the lamp being in alinement with the opening in the front of the casing when the door is closed.

In testimony whereof I affix my signature.

GEORGE E. DAVIS.
